STOCK FEEDING APPARATUS FOR WEB MAKING MACHINES

Pierre Lejeune and Louis de Maillard, Grenoble, France, assignors to Ateliers Neyret-Beylier & Piccard-Pictet (NEYRPIC), Grenoble, France, a corporation of France, and Societe Grenobloise d'Etudes et d'Applications Hydrauliques (SOGREAH), Grenoble, France, a corporation of France.

Filed Sept. 11, 1962, Ser. No. 222,836

Claims priority, application France Sept. 15, 1961
12 Claims. (Cl. 162—337)

This invention relates to apparatus for the feeding of stock onto a web forming surface such as is employed in pulp mills for the manufacture of paper, cardboard, and other types of sheet material.

In the use of apparatus of the indicated type, a frequent occurrence is flocculation and decantation of the charges which are highly detrimental to the quality of the product being manufactured. As a rule, fiber flocculation takes place in the header usually employed in such apparatus for accumulating a quantity of the stock to be fed to the web forming means and especially in those parts of the header where the rates of flow are very low, or where the turbulence of the stock is inadequately developed.

It is the primary purpose of this invention to provide a stock feeding apparatus which will not be subject to flocculation and decantation and their attendant disadvantages.

A more specific object of the invention is to provide a stock feeding apparatus which is capable of being utilized with machines operating over a wide range of speeds, and in which the velocity of flow and the turbulence of the fiber stock remain substantially uniform regardless of the speed at which the machine is operating, and have such values that all possibility of fiber flocculation and decantation is avoided.

The aforesaid objects are achieved in accordance with the invention by providing such apparatus with a closed circuit of pulp carrying liquid embodying the following features:

(a) Means are provided to assure a constant flow rate of the fiber stock that is at least equal to the maximum rate of injection of such stock into the machine for any rate of speed at which the machine is to be operated.

(b) To accommodate the flow rate of the fiber stock to the different speeds at which the machine may operate, the excess of the fiber stock which is fed toward the machine and which is recirculated in the closed circuit, is utilized to control the means for feeding new fiber stock into the circuit, so that such feeding means will deliver to the circuit an amount of pulp carrying liquid which carries sufficient fiber stock to precisely compensate for the fiber stock which is being discharged to the machine.

(c) Means are also provided to deliver to the machine a sufficiently high rate of flow of the fiber stock to make sure that any variations in the speeds at which the machine may operate will not cause excessive decelerations in the rate of flow of the fiber stock at any part of the closed circuit.

The invention contemplates that the means for feeding new fiber stock into the closed circuit may be controlled either by the variation of the liquid surface of the header, or by the variation of the pressure of gas in a closed chamber on such liquid surface of the header, or by the variations in the height of a weir over which the excess fiber stock flows into the header.

In accordance with one form of the invention, the header may constitute a tank, the upper end of which is associated with an overflow chamber having one side thereof functioning as an overflow gate or weir over which the excess fiber stock flows into the header tank.

2

In accordance with another form of the invention, the liquid surfaces of the header tank and the overflow chamber are maintained at a constant differential level, which may be zero in some instances.

5 In accordance with a further form of the invention, the utilization of a gas pressure control of the feeding means may be accomplished by the application of either a positive, negative, or zero pressure, as compared with atmospheric pressure, to the liquid surfaces in both the header tank and the overflow chamber.

10 A closed circuit embodying the aforesaid control features makes it possible to establish the desired rate of flow therein by means of a pump which rotates at a constant rate of speed and which is enabled to circulate the liquid in the circuit with an overall head that is independent of the rate of injection of new fiber stock into the circuit. This assures a high regularity of operation by the circulating pump and consequently, a constant rate of flow of the liquid to the web forming means.

15 20 It has been found that in order to make certain that the machine will operate satisfactorily at highly variable speeds, it is necessary to provide in addition to the means for supplying the liquid stock at a sufficiently high constant rate of flow, an overflow gate or weir at the overflow chamber which is of great length, approximately three or four times the width of the fiber web which is being formed by the machine. Preferably the length of the gate in each machine is a function of the output-rate characteristics of the machine and such that the gate is

25 30 capable of discharging into the header tank large quantities of the liquid stock under a slight head and without the consumption of a considerable quantity of air. It has been found that an overflow gate of such great length also improves the transverse stability of the liquid level in the header tank and therefore tends to equalize the pressures above the place of entry of the new fiber stock into the closed circuit. Also owing to the slight height of the gate there is obtained a satisfactory damping of the heavy turbulences and pressure waves which might occur in the output of the circulatory pump as a result of the instability of the pump.

35 40 It is preferred in accordance with the invention to construct the gate or weir so that it is in fact constituted of a plurality of flow-off gates capable of assuring a stable surface flow throughout the length of the overflow chamber toward the header tank. The individual gates in the system forming the overall gate or weir may be predetermined in number and disposed in parallel relation and lengthwise in the direction of the circuit flow. It is contemplated that the overflow elements forming the individual gates may be coupled in pairs so as to provide between them spouts which channel the surface flow in the overflow chamber to the header tank. A weir construction of this type, it has been found, is of special advantage in maintaining the piezometric head in the fiber or pulp distributing means constant at a controlled value notwithstanding slight fluctuations in the total flow which may be due, for example, to an accidental fluctuation in the speed of the circulating pump.

45 50 55 It is preferred in accordance with the invention to construct the gate or weir so that it is in fact constituted of a plurality of flow-off gates capable of assuring a stable surface flow throughout the length of the overflow chamber toward the header tank. The individual gates in the system forming the overall gate or weir may be predetermined in number and disposed in parallel relation and lengthwise in the direction of the circuit flow. It is contemplated that the overflow elements forming the individual gates may be coupled in pairs so as to provide between them spouts which channel the surface flow in the overflow chamber to the header tank. A weir construction of this type, it has been found, is of special advantage in maintaining the piezometric head in the fiber or pulp distributing means constant at a controlled value notwithstanding slight fluctuations in the total flow which may be due, for example, to an accidental fluctuation in the speed of the circulating pump.

60 65 70 It is to be noted that as the flow of stock, in accordance with the invention, is maintained constant in the area approaching the web forming means for a given machine, regardless of the speed of feed of the machine or the rate of injection of the new stock into the closed circuit, it is possible to predetermine the total flow and also the dimensions of the pulp distributor so that the rate of flow for a particular pulp will be maintained above a given value at every point in the closed circuit. It is thus possible to design a circuit so that in any given portion thereof, the flow of stock through such portion will have a constant given value regardless of the rate of operation of the machine, thereby eliminating the possi-

bilities of flocculation and decantation of the charges which frequently occur in known plants due in the main to excessively low speeds at certain parts of the circuits thereof and to an inadequately developed turbulence.

A better understanding of the advantages and features of the invention will become more apparent from a perusal of the following description of several embodiments of the invention which are given by way of example, when read with reference to the accompanying drawings, in which

FIG. 1 is a schematic view showing in vertical section a closed circuit embodying the invention and provided with a closed header which may be under positive or negative pressure;

FIG. 2 is a schematic elevational view, partly in section, of the apparatus shown in FIG. 1, the view being taken along the line 2—2 of FIG. 1;

FIG. 3 is a perspective view of an end portion of the overflow gate associated with the header;

FIG. 4 is a schematic vertical sectional view of the stock distributor included in the closed circuit; the view being taken along the line 4—4 of FIG. 5;

FIG. 5 is a horizontal sectional view of the stock distributor taken along the line 5—5 of FIG. 4;

FIG. 6 is a schematic vertical sectional view showing another form of header that may be employed in the closed circuit; and

FIG. 7 is a view similar to FIG. 6 showing still another header construction embodying the invention.

As above indicated, FIG. 1 of the drawings shows a stock feeding system in which the parts are arranged in a closed circuit in accordance with the invention so as to effect a constant flow rate of the stock material in fully distributed condition in the liquid regardless of the speed of the machine or the rate of injection of the new stock, and without danger of flocculation and decantation of the stock at any portion of such system. In such system, the material to be circulated is drawn from a header tank generally designated by the reference character A. The header tank is supplied by the new stock feeding means generally designated B and by the liquid stock which is in excess of that required by the machine C and which flows into the upper end of the header tank A from an overflow chamber generally designated D. The liquid stock resulting from the combination of both of these sources of supply is withdrawn from the header tank A by a pump P and forced by the latter into a distributor generally designated E for assuring that the stock fibers supplied from both sources are distributed evenly throughout the liquid before the constant recirculating flow is passed through the pipe 3 to the slice F.

The header tank A is in the nature of a hopper the body 1 of which has a substantially rectangular cross-sectional area and is inclined at an angle of approximately 45° with the horizontal. The lower end of the hopper body is connected with a pipe 11 which leads to the pump P. The entry end of the pipe 11 is located approximately centrally of the width of the tank body 1 and between two vertically disposed baffle walls 9 which rise from the bottom of the tank body near such pipe entry end. Also centrally located between the lower ends of the baffle walls 9 is the discharge end of a diffuser 18 which forms part of the stock feeding means B and which is of a construction known to the art. The intake of the diffuser is regulated by a gate valve 31 that is operated by a servo-motor 30 which is controlled by the excess flow returning to the header tank as will hereinafter become more clear.

The new stock supplied to the header tank by the diffuser 18 is a very even mixture of water and fibers and is directed toward a baffle 10 which is formed between the lower ends of the baffle walls 9 against the opposite wall 36 of the tank body 1 so as to dispense the charge being delivered by the diffuser into the excess stock material substantially filling the header tank. The two baf-

fe walls 9 are built high enough in the tank body 1 to effect as much as possible a uniform distribution of the new stock from the diffuser 18 in the excess stock in the tank before the combined flows pass out of such tank body into the pipe 11.

The pump P delivers the circulation flow through a pipe 12 into the distributor E which is shown more clearly in FIGS. 4 and 5 of the drawings. It will be noted from a comparison of these figures with FIG. 1, that the distributor E comprises a casing that is generally cylindrically-shaped with its central axis disposed transversely to the direction of the circulation flow in the machine. The length of the casing is at least equal to the width of the fiber sheet which is being formed by the machine C. The casing of distributor E is formed so that adjacent to the discharge slot 13 thereof it is provided with a baffle 2 which directs the circuit flow into a double curve as it passes through the distributor. The baffle 2 has a length equal to the length of the distributor casing, or the distributing chamber thereof. It will also be noted from these figures that the discharge end of the duct 12 is substantially tangent to the periphery of the distributing chamber so that the stock is introduced tangentially into such chamber and flows in a curve towards the baffle 2 which turns it back through an angle of approximately 180° to direct the flow across the distributor to the opposite wall portion thereof above the discharge end of the duct 12. The flow is then turned through another approximately 180° curve toward the discharge slot 13, as is indicated by the flow arrows in FIG. 4 of the drawings. In order to dampen this double helicoidal movement of the stock through the distributor E, the duct 12 is constructed so that cross-sectional area decreases towards its discharge end. As will be observed from a comparison of FIGS. 2, 4 and 5 of the drawings, the duct 12 has a circular configuration at the terminus of its entry end and from adjacent such terminus has a generally flattened form which increases in width from the entry end W-W' thereof to the discharge end V-V' thereof so that the opening formed by the latter and constituting the entry opening for the distributor casing is slot-like in configuration. Accordingly, the decrease in cross-sectional area of the duct 12 is accomplished by progressively decreasing its height toward the discharge end V-V'. This decrease is quite substantial, approximately 30%, i.e., the cross-sectional area of the duct 12 at its discharge end V-V' is about 30% less than the cross-sectional area of the duct at its entry end W-W'.

It will be observed more clearly in FIG. 5, that the discharge end of the duct or pipe 12 has a width approximately one-third the length of the distributor casing and is connected with the central portion of such chamber. It has been found necessary that in order to make the flow of stock discharged by the duct 12 into the distributor, feed outwardly to the ends of the distributor chamber instead of flowing only through the central portion of such chamber, a second baffle 2' capable of accomplishing this purpose should be provided in the path of the liquid flow shortly after it is discharged into the distributor E and before it comes into contact with the upper baffle 2. This second baffle 2' is positioned centrally of the distributor E adjacent to the discharge end of duct 12 and has a length which approximates the width of the duct 12. Thus the stream of stock discharged by the duct 12 will shortly after its entry into the distributor E strike baffle 2' which will further cut down its speed of flow and direct substantial portions thereof to the two ends of the distributor chamber, as is indicated by the arrows in FIG. 5, the stock then rising throughout the length of the chamber into contact with the upper baffle 2. As a result of the action of the duct 12, and baffles 2, 2', the rate of flow of the stock will be regularly divided so that the flow rate of the stock reaching the discharge slot 13 will have a perfectly even distribution

throughout the entire width of such slot without breaking the homogeneity of the stock fed into the duct 12.

The discharge slot 13 extends substantially the entire length of the casing of distributor E and has a length equal to the width of the fiber web being formed by the machine. The stock delivered to conduit 3 is conducted by the latter to the slice F and to the overflow chamber D both of which are connected to the upper discharge end 14 of such conduit. The conduit 3 throughout its length is of uniform width, namely, a width equal to the width of the fiber web being produced. The height of the conduit 3 progressively increases towards the discharge end 14 of the conduit, so that at the latter its cross-sectional area is substantially double the cross-sectional area of the slot 13. The relation of such cross-sectional areas is such that the rate of circulatory flow through such elongated conduit and delivered thereby is at all points sufficiently high enough to prevent flocculation and decantation of the charges, and such that the stock is not decelerated to disadvantage in the region of the slice F.

The slice is composed of two lips 15, 16 and a pivoted plate 4 which form a flattened discharge nozzle having a discharge aperture of a width equal to the width of the web which is being formed on the traveling belt of the machine C in the usual manner. The lips 15 and 16 are rigid and integral with the conduit 3 and are slightly convergent toward the discharge end of the nozzle. The upper lip 16 terminates short of the terminal end of the nozzle and the top outer end of the nozzle beyond such lip is formed by the outer free end of the pivoted plate 4. It will be noted in FIG. 1 that the plate 4 is hinged for adjustable movement about a shaft 17 to provide a control for the flow of the stock to the forming belt of the machine. The shaft 17 which forms part of the slice, is mounted on the exterior of the upper lip 16 so as not to interfere with the flow of the stock to the forming belt and is in position to enable ready adjustment of the plate 4 to comply with the requirements of the machine.

The portion only of the stock flowing up through the conduit 3 that is required to form the particular size of web it is desired to manufacture, passes through the slice to the forming belt of the machine. The remaining portion of the stock flows up through an elongated discharge opening or slot 35 provided in the upper end of the conduit 3 above the slice F. Connected at its lower end to discharge slot 35 is the overflow chamber D through which the excess stock passes on its way to the header tank A. As will be seen from a comparison of FIGS. 1-3 of the drawings, the overflow chamber D is a unit assembly which is pivotally connected by means of a shaft 8 to the wall 36 of the header tank A in order that it may be swung away from the conduit 3 to a position in which the parts thereof may be made more accessible for cleaning and repair. As is shown more clearly in FIG. 3 of the drawings, the unit above the line of pivot 8'-8" is provided with a wall 37 which forms a continuation of the header wall 36 and has a width equal to the width of the latter. It will be understood therefore that the width of the unit is equal to the width of the header tank so that the latter receives a flow of the excess material extending throughout its entire width. This width of both the overflow unit and the header tank is equal to the length of the discharge slot 35 and consequently equal to the width of the conduit 3 and the web being formed on the machine. However, the overflow unit is constructed so that the actual overflow surface thereof is substantially greater than the width of the fiber web being formed. It has been found that best results are obtained if the overall width of the overflow surface provided for the excess stock is approximately three or four times the width of the fiber web formed in the machine. As has been previously indicated, it has been found that such a long overflow surface is necessary for the satisfactory operation of a machine which works at variable flow rates while operating over a wide range of speeds.

The aforesaid result is obtained in the construction disclosed in FIG. 3 by extending through the inclined wall 37 of the overflow unit a plurality of vertically disposed hoppers 6 which are in communication at their lower ends with the discharge slot 35 of the conduit 3. The hoppers 6 have a common end wall 7 which extends down to the slot 35 and has a width equal to the width of the inclined wall 37. The hoppers are formed in spaced relation along the end wall 7 and each have additionally two side walls 5 provided at their upper ends with rolled edges 38, 38 which constitute the overflow edges of the hoppers. The other ends of the hoppers are provided with raised end portions 39 which prevent the discharge of the stock over such ends and cause the stock to flow over the edges 38 thereof. It will thus be understood that the excess stock flowing up through the slot 35 will enter the lower ends of all of the hoppers 6 extending across the entire width of the upper end of the header tank A, and will rise in such hoppers to overflow the edges 38, 38 thereof, and flow down between the side walls 5 of the hoppers to the inclined wall 37 and from thence into the header tank A, as is indicated by the arrows f in FIGS. 2 and 3 of the drawings. Because the stock is forced to flow over the edges 38, 38 of the hoppers 6 rather than the ends of such hoppers blocked by the raised end portions 39, the combined overflow surface attained is approximately three or four times the width of the overflow unit D and the header tank A. As the provision of these hoppers necessarily restricts the overall cross-sectional area of the overflow chamber, the wall 7 of the unit is inclined outwardly from the discharge slot 35 and each of the side walls 5 of the hoppers 6 is convexly-shaped to maintain the combined cross-sectional area of the spouts substantially constant from the discharge slot 35 to the edges 38 of such hoppers and substantially equal to the cross-sectional area of such discharge slot 35.

The overflow unit D assures a nearly constant liquid surface level N1, in FIG. 1, above the distributor E. Means are also provided so that the liquid surface N2 in the header tank A is utilized to control the input by the feeding means B of the new stock into the header tank so that the surface level N2 will maintain itself at a slightly lower level than that of N1. In this manner the useful output admitted into the header tank A by the feeding means B will compensate accurately for the stock that is utilized by the slice F to form the fiber web in the machine. The means for accomplishing this purpose may be any suitable means known to the art for controlling the servo-motor 30 associated with the gate valve 31, such as the electrical device designated 19 for indicating variances of the level N2 from a given height.

As is shown in FIG. 1 the upper end of the header tank A may be closed to form a closed chamber 39 above the surface levels N1, N2 and in which a pressure or vacuum may be built. With such a construction, it is possible to regulate the rate of discharge of the stock by the slice F into the machine C without affecting the operation of the pump P, since the intake and discharge of the pump will be subject to the same pressure or vacuum through the header tank A, and the overflow chamber D, conduit 3 and distributor E, respectively, irrespective of the change in the rate of flow of the stock through the slice F. The pressure in the chamber 39 may be controlled for example, with the aid of a vacuum pump 20 connected by a pipe 21 to chamber 39 and controlled to modify the pressure in the latter as needed. The chamber may have a manometer 22 to give a constant reading of the pressure in chamber 39 and a hand valve 23 may be provided to enable manual control of such pressure. There may be associated with the hand valve 23 an automatic valve 24 capable of providing a fine control of such pressure.

In FIG. 6 of the drawings there is shown an open header tank A' and the overflow chamber D' is formed

by an end wall 7' rising vertically from the discharge slot 35' of the conduit 3', side walls (not shown) and a flow-off gate constituted of a plate 25 extending across the width of the header tank and pivoted at its lower horizontal edge for axial movement about the pivot 26. By changing the position of the plate 25 about its pivot 26 the height of the flow-off gate may be regulated so as to adjust the rate of flow of the stock through the slice F to the machine. In this construction, the level of the header tank A may be regulated by an adjustable automatic device 19 and servo-mechanism 29 in the same manner as previously described with respect to the embodiment of FIG. 1. In this construction, however, the liquid level of the header tank A' is maintained at a slightly lower height than the liquid level in the header tank A.

The embodiment of FIG. 7 shows a submerged type of flow-off gate 27 which may be incorporated in either an open header A' as shown in FIG. 6, or in a closed header A" as shown in FIGS. 1 and 7. It will be noted that the overflow surface of the gate 27 is far enough below the liquid surface that the discharge thereover is submerged and that the liquid levels in the header A" and in the overflow chamber D" are joined so as to in effect constitute one continuous surface, as indicated by the reference N3 in FIG. 7 of the drawings. In the case of a closed header, such as the header A" this level N3 will remain constant and the extensible vertical baffle or gate member 27 should be set at such a height that the flow from the overflow chamber D" toward the header tank A" is accomplished without any appreciable loss of charge. The rate of flow of the stock through the slice F in this construction, may be controlled in the manner described with respect to the embodiment of FIG. 1, namely, by controlling the pressure in the chamber 39' above the level N3.

In the case of an open header, such as shown in FIG. 6, the level N3 will be variable and can be utilized in the manner of the embodiment of FIG. 6, to control the rate of injection of the new stock into the header tank A". In this embodiment, the level mark may be regulated by adjustment of the height of the extendable vertical baffle 27 so that the rate of the flow above the baffle will remain constant and so as to prevent countercurrents through such flow. As in the case of the embodiment of FIG. 6, the introduction of the new stock into the bottom of the header tank A" may be controlled by the servo-mechanism 19, 29 to maintain the level N3 at a predetermined height.

While we have hereinabove described and illustrated in the accompanying drawings, preferred embodiments of the invention, it will be understood by those skilled in the art that various changes and modifications thereof may be made without departing from the spirit of the invention, or the scope of the following claims.

We claim:

1. A device for feeding stock to a web making machine, comprising arranged in a closed circuit, a header tank and an overflow chamber positioned in adjacent relation so that stock rising in such chamber will overflow into the upper end of said header tank, means for feeding new stock into said header tank below the surface level thereof and into intermixture with the stock therein from said overflow chamber, means spaced from said header tank in the circuit for distributing the stock, means for pumping the combined mixture of stock from said header tank into said distributor means at a given substantially constant flow rate greater than the rate of flow of the stock required by the machine and such that the flow in all portions in such circuit is sufficiently high to prevent flocculation, a slice associated with the machine and constructed and arranged to take a portion of the volume of stock fed to said distributor means, means for conveying from said distributor means such portion of the stock to said slice and the stock in excess thereof to the

bottom end of said overflow chamber, and means for controlling the rate of flow of the stock through said slice to the machine.

2. A device such as defined in claim 1, including means controlled by the excess of stock returned to said header tank for controlling the rate of feed of said feeding means to compensate the circuit exactly for the stock removed therefrom by said slice and thereby maintain substantially constant the flow rate of the stock to said fiber distributor means.

3. A device such as defined in claim 2, in which said feeding means includes an adjustable feed valve, and in which said controlled means includes means for actuating said feed valve, and means associated with the liquid level in said header tank and operative upon a change in such level from a given height to operate said actuating means to cause said valve to adjust the flow of said feeding means so as to restore such given height.

4. A device such as defined in claim 1 in which said flow controlling means comprises an adjustable baffle having one edge disposed in the flow of said circuit and movable relative to such flow to vary the rate thereof past such edge.

5. A device such as defined in claim 1, in which said distributor means comprises a housing having a discharge slot substantially equal in width to the width of the fiber web being formed and an entry opening having a width considerably less than the width of said discharge opening, the chamber in said housing having a width approximately the width of the fiber web and having located therein flow directing baffle means of a width equal to the width of said chamber for changing the path of flow of the stock admitted through said entry opening.

6. A device such as defined in claim 5, in which said distributor means has located within the distributing chamber thereof a second flow directing baffle means of a width considerably less than the width of said chamber for causing a portion at least of the stock admitted through said entry opening to flow toward the ends of said chamber before coming into contact with said first baffle means.

7. A device such as defined in claim 1, in which the stock in said overflow chamber passes over an overflow edge having an overall width considerably greater than the width of the web being formed in the machine.

8. A device such as defined in claim 1, in which said overflow chamber includes overflow means having a width substantially equal to the width of said header tank and having an overflow edge providing an overall width considerably greater than the width of said header.

9. A device such as defined in claim 8, in which said overflow means is composed of a plurality of overflow ducts each of which has a pair of spaced overflow edges arranged transversely to the width of said header tank.

10. A device for feeding stock comprising an overflow chamber for directing excess of the stock into the upper end of a header tank, said overflow chamber comprising a plurality of individual ducts arranged as a series in spaced side-by-side relation and having opposing side walls formed at their upper edges to provide liquid overflow edges over which the stock flows into the spaces between said ducts, the end walls of said ducts being configured to direct the stock rising in said ducts over said side overflow edges.

11. A device for feeding stock comprising a distributor for distributing the stock comprising a generally cylindrically-shaped casing having a length approximating the width of a fiber web to be formed from such stock and having an elongated, slot-like entry opening extending longitudinally of said casing and arranged in tangential relation to the periphery of the chamber therein, and said casing having a longitudinally extending discharge slot of a length substantially equal to the length of said casing, the length of said entry opening being considerably less than the length of said discharge slot, said casing containing within the chamber thereof in spaced opposed relation to said entry opening a baffle element

having a length equal to the length of said discharge opening and positioned on the wall of said case with relation to said entry opening and discharge slot so that it is located in the path of flow of the stock from said entry opening to said discharge slot, said baffle element being configured to change the direction of such path of flow so as to cause the stock to reverse its direction in said chamber twice before passing out through said discharge slot.

12. A device for feeding stock to a web making machine, comprising a closed circuit, means connected to one point of said circuit for variably feeding a flow of stock into said circuit, and means connected to a second spaced point of said circuit for discharging stock into said machine including a discharge port having a predetermined width comparable to the width of the web being formed, said closed circuit including a first portion extending between said points of connection of said feeding means and said discharge means and wherein the stock flow is substantially constant and in excess of the maximum output flow possible in said discharge means, and said closed circuit including a second portion separate from said first portion and extending between said points of connection of said discharge means and said feeding means and being provided with flow off means for controlling said feeding means, so as to maintain the stock flow substantially constant in said first circuit portion, said first point being located between the start of said first circuit portion and the end of said

5 second circuit portion, and said second point being located between the end of said first circuit portion and the start of said second circuit portion, said first circuit portion comprising a pump, a first conduit connected at its entry end to said pump and having a width substantially less than said discharge port, a second conduit connected at its discharge end to said discharge means and having the same width as said discharge port, and a distributor located between said two conduits and connected to the discharge end of said first conduit and to the entry end of said second conduit, said distributor having deflection means for diverting laterally the stock fed therein from said first conduit, and said distributor having the same width as said discharge port and discharging into the entry end of said second conduit.
